UNITED STATES PATENT OFFICE.

JOHN T. CHRISTIE, OF TROY, NEW YORK.

HOT-GAS VALVE.

SPECIFICATION forming part of Letters Patent No. 541,990, dated July 2, 1895.

Application filed December 21, 1894. Serial No. 532,547. (No model.)

To all whom it may concern:

Be it known that I, JOHN T. CHRISTIE, a citizen of the United States, residing at Troy, county of Rensselaer, and State of New York, have invented certain new and useful Improvements in Hot-Gas Valves, of which the following is a specification.

The invention relates to such improvements, and consists of the novel construction and combination of parts hereinafter described and subsequently claimed.

Reference may be had to the accompanying drawings, and the letters of reference marked thereon, which form a part of this specification.

Similar letters refer to similar parts in the several figures therein.

Figure 1 is a central vertical section of my improved valve in an open position. Fig. 2 is a similar section, taken at right angles to the section-plane of Fig. 1, showing the valve closed. Fig. 3 is a cross-section of the gate taken on the broken line 3 3 in Fig. 1.

A is the valve-case, which is provided with the passage A', surrounded by the usual attaching-flanges A² and annular gate-seat A³.

B is a circular slide-gate adapted to engage with the seat A³ to close the valve in one direction in the usual manner.

A⁴ is a pocket in the case adapted to receive the gate when the valve is opened.

A⁵ is the valve-stem screwed into the upper edge of the valve and movable endwise through the usual stuffing-box A⁶.

The slide-gate is made hollow, forming an inclosed chamber B' which is divided into two compartments B² and B³ by the diaphragm B⁴, which connects the opposite side walls of the chamber. The two compartments

communicate with each other through a passage B⁵ at the lower end of the diaphragm which does not extend to the bottom of the chamber. The upper edge wall of the chamber is provided with two screw-threaded

openings, one in each compartment. Each of these openings is provided with a pipe or tube screw-threaded at its lower end and inserted to form a water-tight joint. One of these pipes, as C, is the inlet-pipe leading into the compartment B², and the other pipe C' is the outlet-pipe adapted to discharge from compartment B³. Each of the pipes is movable

endwise through a pair of stuffing-boxes C² and C³ and within a fixed pipe. The fixed pipe C⁴ is adapted to be coupled, as by coupling C⁵, with a water-supply pipe, and the fixed pipe C⁶ with a waste-pipe. The pipes C⁴ and C⁶ are respectively screwed into the upper stuffing-boxes, which forms a watertight connection between the movable members of each set of telescoping pipes. The lower stuffing-boxes form a gas-tight connection between the movable pipes and the valve-case. The glands C⁷ and C⁸ are supported by bolts C⁹ connecting the gland-flanges C¹⁰ with their respective boxes, as shown in Fig. 2.

The upper stuffing-boxes are supported at the proper distance above the lower boxes by means of the connecting-bolts C¹². As these bolts hold the stuffing-boxes C² rigidly and at a considerable distance from the fixed valve-case, they hold the said boxes and the pipes C⁴ and C⁶ in a stable manner, and stability is further insured by the couplings C⁵, adapted to connect with fixed outlet and inlet pipes. The construction enables the rubber pipes heretofore employed in connection with similar valves to be dispensed with and also affords a very stable and smoothly-operating connection between the pipes C C' and C⁴ C⁶, whereby the valve is accurately guided to and from its seat and binding of the parts obviated. Both ends of each of these bolts are provided with a fixed stop or annular flange, as C¹³, and screw-threaded. The lower ends are screwed into threaded apertures in the box-casting and the upper ends are passed through apertures in the casting of the upper stuffing-boxes until the upper flanges engage the casting, where they are supported by nuts, as C¹⁴.

By providing the supply-pipe with a constant supply of water under pressure, I am able to maintain with the apparatus above described a continuous current of water through the slide-gate which will absorb and carry off all excess of heat which would otherwise be retained by the gate when used in connection with hot gases. Without some means for absorbing and carrying away the excessive heat communicated to the open gates suspended just above the passing hot gases the lower edges of the gates are soon burned away and destroyed. I am thus able

to greatly prolong the life and efficiency of the gates. The diaphragm B⁴ also serves to strengthen the chamber-walls of the gate, whereby comparatively thin and light walls are enabled to resist the gas-pressure. The gate-seat is also protected from the hot gas by circulating water through the water-passage D formed in the casting comprising the valve-case. The position and direction of this water-passage are indicated partly by solid and partly by dotted lines.

D' and D² respectively show the inlet and outlet to which the supply and waste pipes are respectively attached.

I am aware that concentric water-supply pipes have been combined with a hydraulic crane in manner to provide for their rotation, and also to permit a slight endwise motion when the crane-mast is lifted by pressure in the lifting-cylinder. It is characteristic of my improvement that the telescoping pipes have no rotary motion and that provision is made for endwise movement of slide-gate pipes each through and beyond two stuffing-boxes separate from each other but supported

by the valve-case, said pipes being also combined and adapted to move in and out of other pipes rigidly fixed to the boxes and valve-case and extended beyond said boxes.

What I claim as new, and desire to secure 30 by Letters Patent, is—

The combination of the chambered slide gate, the fixed valve case having stuffing boxes C³, the stuffing boxes C² supported from the case by bolts C¹², the water-supply-and-discharge pipes connected to the stuffing boxes C² and fixed therein against either endwise or rotary motion and provided with couplings C⁵, and the telescoping pipes C, C' fixed to the slide gate and moving freely through both 40 stuffing boxes and within the said water-supply-and-discharge pipes beyond the boxes, substantially as set forth.

In testimony whereof I have hereunto set my hand this 15th day of December, 1891.

JOHN T. CHRISTIE.
